SLOT CLOSURE ACTUATING MECHANISM

Arthur C. Patch, Santa Monica, Calif., assignor
to North American Aviation, Inc., Inglewood,
Calif., a corporation of Delaware

Application December 31, 1942, Serial No. 470,775

3 Claims. (Cl. 244—42)

This invention relates to improvements in actuating mechanism for closures, and more particularly to mechanism for the operation of doors controlling the opening and closing of slots in airfoil surfaces.

In variable lift airfoil surfaces it is customary to provide intersurface slots and to regulate the action of the slot, in allowing a flow of air from one surface to the other, by providing a movable door or doors at the ends of the slot. Variable slots are also frequently used which may be regulated by having one slot wall formed by a surface of a member relatively movable with respect to the fixed member contributing the opposite wall of the slot. Depending upon the configuration of the slot walls and the allowable movement of the one member, the slot may be entirely closed off upon the movement of the members into contact or the slot may be closed somewhere along its length so as to cut off flow therethrough but at the same time, at the mouth or at the mouth and exit of the slot may be left gaps in the airfoil surfaces. Such gaps detract from the aerodynamic efficiency of the airfoil by creating interruption of the laminar flow and consequent drag. In such a case it is the practice to provide a movable closure whereby the slotted airfoil can be restored to the equivalent of a substantially unbroken airfoil contour at such times when the slot is not employed.

A variable slot of the type which requires a closure at its mouth is produced in airfoils fitted with high lift flaps. As is well known, such flaps normally carry out the original airfoil contour but can be lowered or pivoted with respect to the fixed main or forward part of the airfoil to provide increased lift at slow speeds. When such flaps are moved into operative position, it is usual for the relative movement of the slot nose with respect to the fixed airfoil section, to form a slot therebetween extending upwardly and rearwardly from the lower surface to the upper surface. Such flaps pivot downwardly and for reasons of clearance and due to provision for desirable slot characteristics, the mouth of the slot is relatively wide and even with the flap in normal position the trough that remains is of considerable width, depth and span.

The present door and its operating mechanism are intended for use in closing off a surface opening of this type when the flap is in normal position. The addition of an accessory of this nature should not add to the complexity of the operation of the aircraft and accordingly it is desirable that the mechanism operate automatically

in conjunction with the operation of the flap, that it be entirely enclosed within the airfoil surface and that its operation be correctly timed with respect to that of the flap. In attaining this last operational characteristic it is preferable that the door open fully upon initial movement of the flap away from its neutral position and remain open until the flap is again restored to the aligned position.

10 The objects of the present invention are to provide a closure operating mechanism incorporating the desirable characteristics outlined above and by reference to the accompanying drawing and following description, a full understanding of the construction and operation of this mechanism may be attained.

In the drawing:

Fig. 1 is a sectional view of a portion of a variable lift airfoil fitted with a flap of the slot opening type and with a movable closure for the slot mouth opening;

20 Fig. 2 is a section similar to Fig. 1 taken at a point adjacent the location of the closure operating mechanism and showing the closure in gap closing position; and

25 Fig. 3 is a section corresponding to that of Fig. 2 but showing the closure in open position.

Referring in detail to Fig. 1, therein is shown in section the after end of an airfoil consisting 30 of an upper surface skin sheet 10, a lower surface skin sheet 12, a rear spar or bulkhead 14 and a pivotally hung flap 20. Extending from the spar is a bracket 22 and two or more such brackets are provided at spaced locations to provide for the complete mounting of the flap 20. This is accomplished at each bracket by means of a pivot 34 at the projecting end of the bracket from which extends a simple link 36 which at its other end may be pivotally connected to the flap, as 35 at 38.

40 Extending spanwise through the airfoil section is a torque tube 24 supported for rotational movement in the brackets 22. Adjacent to each point of support for the flap 20, or adjacent to as 45 many such points as may appear necessary, the torque tube carries collars 26 from which project lever arms 28 and 29. Pivotal connected to the projecting end 30 of each of the arms 28 are push-pull links 32 which each in turn rigidly connect 50 to the flap 20 adjacent its leading edge. Thus it is obvious that with this mounting of the flap and the linkage connection to the torque tube, rotation of the latter will cause the flap to be swung rearwardly and downwardly to a displaced position as shown in Fig. 3 and this move-

ment will create an intersurface slot between the nose of the flap 20 and a curved plate 68 which forms a rear wall for the airfoil portion 10-12.

The mechanism employed to cause rotation of the torque tube 24 is conventional and may consist of a hydraulic motor such as is fragmentarily shown at 44. The end 42 of the piston of this motor is pivotally connected by a link 40 to one of the arms 29 and thus by remote control of the motor, the pilot or operator can cause the raising and lowering of the flap 20.

As previously stated, the streamline profile of the airfoil portion defined by the upper and lower surfaces 10 and 12 is continued to a narrow trailing edge by the surfaces of the flap 20 but due to provision for the opening of the previously mentioned intersurface slot between the nose of the flap and the rear end of the fixed airfoil portion, this contour would be interrupted by a gap on the lower side of the combination to the rear of the spar 14 and the gap would be roughly of triangular section extending halfway into the depth of the airfoil. In order to cover this gap, a closure or door 16 is pivotally mounted as at 18 in the gap in flush continuation of the surface 12.

With the flap lowered, as in Fig. 3, and the slot opened, it is necessary that the door be swung back to allow unimpeded airflow through the slot. This swinging back of the door is accomplished automatically in consequence of the initial movement of the flap. Likewise return of the door to closed position occurs automatically upon the return of the flap to neutral position. This operation of the door 16 is obtained as a result of the flap operating movements of the torque tube 24 by novel mechanism. The door is fitted with a bracket 46 constituting a lever arm at the projecting end 48 of which is pivotally attached a connecting rod 50. This rod extends to merge into a guide portion 52 characterized by bifurcated arms 54 which straddle the torque tube 24 as shown with just sufficient clearance to permit sliding movement of the arms on the tube. The member 52 may also be bifurcated in a direction parallel to the plane of the drawing so that, in such a case, there would be in actuality, four of the arms 54. The slot formed by this second bifurcation would extend nearly the full length of member 52 to terminate at the curved dotted line shown thereon.

Affixed to the torque tube 24 is a collar 56 and this is positioned between the two pairs of arms 54. This collar projects along a portion of its periphery in the form of a flange and the flange portion has cut therein a cam slot of which the major portion 60 is substantially concentric to the tube 24. The remainder 64 of the slot extends at an angle to the portion 60 being directed inwardly toward the tube. There is a pin 62 extending between the two faces of the member 52 and with the door closed as in Fig. 2, this pin extends through the cam slot being disposed at the extreme end of the slot portion 64. The exact shape of the portion 64 is such that after initial rotation of the torque tube 24 in a counter-clockwise direction, so as to initiate lowering of the flap 20, the pin 62 is forced to move outward from the tube. Because of the bearing of the arms 54 on the surface of the tube, this movement is forced to occur radially outward from the tube. The movement of the pin and consequently of member 52 and its connecting rod portion 50 is transmitted to the door 16 and is of sufficient duration as determined by the slot portion 64 to

fully open the door to the position shown in Fig. 3 wherein the free edge of the door 16 seats in a groove portion 70 formed in the edge of the curved plate 68. As the rotation of the tube 24 continues, the pin 62 enters the slot portion 60 and the radial movement of the pin ceases but nevertheless, the pin does not interfere with continued lowering movement of the flap 20. When the tube 24 is later turned in a clockwise direction to retract the flap, the cam slot 60 moves past the pin 62 until the portion 64 again comes into engagement therewith and is effective to cause movement of the pin radially toward the center of the tube with consequent closing movement of the door 16, followed by complete return of the flap to neutral.

While this application of the present mechanism has for purposes of illustration been made in connection with a slot closure in an airfoil, it is capable of being employed in many other installations where its functioning would be of advantage and hence it is not intended that the invention be limited in any way by its association with such an installation but only in conformity with the scope of the appended claims.

I claim as my invention:

1. An aircraft wing system comprising a fixed wing and a movable member associated therewith in a slot-forming relationship, a rotatable actuating element for the operation of said movable member, a closure element normally forming a streamlined continuation of the aligned surfaces of said wing and said movable member, said closure element having a pivotal support upon said wing and a spaced pivotal connection, a variable radius cam means fixedly attached to rotate with said actuating element, a link engaging said cam means and the said spaced pivotal connection of said closure element whereby rotation of said actuating means for slot-forming operation of said movable member rotates said slot closure element into its slot-opening position, parallel links pivotally supporting the movable member at spaced points from a pivot axis supported by the fixed wing, and a force transmitting linkage having elements interconnected at a pivot point, the said linkage operably interconnecting the movable member with the rotatable actuating element, the said parts being so organized that the said pivot axis, the said pivotal connection, and the centerline of the rotatable actuating element form the apexes of a triangle on one leg of which lies the said pivot point when the movable member is in a neutral position, and whereby the said pivot point is displaced to lie on an adjacent leg of the triangle when said movable member is moved to fully operative position.

2. In an aircraft wing system, a main fixed wing, a flap movably associated with the trailing edge of said wing such that a slot is formed between said flap and said wing, a slot closure pivotally supported upon said wing, a rotatable actuating member journaled within said wing, brackets supported from said wing, links pivotally interconnecting said brackets with said flap, a lever attached to rotate with said actuating member, a horn element rigidly attached to said flap and pivotally connected to said lever, whereby upon rotation of the actuating member the said flap is caused to move rearwardly and downwardly with each point of pivotal support on the flap constrained to follow an arcuate path centered on the pivot point of attachment of the respective link to its bracket so that a slot is opened between the nose of said flap and the trailing

edge of said fixed wing, a flanged element attached to rotate with said actuating member, said flanged element having a cam slot of varying radius from its center of rotation cut into said flanged portion, and interconnecting means pivotally connected adjacent one terminal portion to said closure element and having a pin associated with its opposed terminal portion engaging the said cam slot in said flanged element, a pair of fork arms extending in substantial parallelism from said opposed terminal portion to embrace and be guided upon said actuating member whereby said interconnecting means is constrained to linear motion and causes slot closure operation coincident with initial flap movement rearwardly.

3. The combination in a control surface installation, a control surface pivotally mounted at the ends of parallel swinging links; the said links in turn being pivotally connected to fixed structure; an actuating member mounted to respond to control impulses; a lever extending from said actuating member to pivotal connection with a rigid projection extending from the control sur-

face; a slotted cam plate extending from said actuating member; an interconnecting member formed with fork arms slidingly embracing the actuating member; the interconnecting member extending substantially radially with respect thereto and terminating in a pivot connection; a hinged door pivotally mounted adjacent the nose of the control surface; a pivot connection attached to the said door offset from the hinge axis thereof and operably connected to the pivot connection on the said interconnecting means; and a cam follower projecting from the said interconnecting means, at a point on the line drawn through the said pivot connection and the axial centerline of the actuating member, to engage said slotted cam; the said parts of the combination being so organized as to cause full opening of said door coincident with initial rearward and downward movement of the control surface about a center of pivotation moving on the arc of a circle centered on the axis of pivotation of the parallel links where they are connected to said fixed structure.
